US0D1033740S

(12) **United States Design Patent** (10) **Patent No.:** **US D1,033,740 S**
Agha et al. (45) **Date of Patent:** **** Jul. 2, 2024**

(54) **HAIR STYLING AND HAIR CARE APPARATUS**

(71) Applicant: **Dyson Technology Limited**, Wiltshire (GB)

(72) Inventors: **Apoory Agha**, Singapore (SG); **Emily Mary Menzies**, Bristol (GB); **Nicklaus Yu**, Singapore (SG); **Simon Brian McNamee**, Bristol (GB)

(73) Assignee: **Dyson Technology Limited**, Malmesbury (GB)

(**) Term: **15 Years**

(21) Appl. No.: **29/806,189**

(22) Filed: **Sep. 1, 2021**

(30) **Foreign Application Priority Data**

Mar. 2, 2021 (EM) 008448450-0005

(51) **LOC (14) Cl.** **28-03**

(52) **U.S. Cl.**

USPC **D28/18**

(58) **Field of Classification Search**

USPC D28/12, 13, 18, 19

CPC A45D 20/00; A45D 20/12; A45D 20/122

(57) **CLAIM**

The ornamental design for hair styling and hair care apparatus, as shown and described.

DESCRIPTION

FIG. 1 is a perspective view of a hair styling and hair care apparatus, illustrating our new design;

FIG. 2 is a front view thereof;

FIG. 3 is a rear view thereof;

FIG. 4 is a side view thereof;

FIG. 5 is an opposite side view thereof;

FIG. 6 is a top view thereof; and,

FIG. 7 is a bottom view thereof.

The broken lines illustrate portions of the hair styling and hair care apparatus that form no part of the claimed design.

1 Claim, 7 Drawing Sheets
